UNITED STATES PATENT OFFICE

2,552,753

APPARATUS FOR PRODUCING METAL COMPOUNDS BY ELECTROLYSIS

Martin von Schulthess, Zurich, Switzerland

Application December 5, 1946, Serial No. 714,189
In Switzerland December 11, 1945

2 Claims. (Cl. 204—263)

1

This invention relates to electrolytic cells for the production of metal compounds and more particularly to cells primarily designed for producing copper compounds from pure copper or copper containing metal mixtures or alloys.

An object of the invention is to provide electrolytic cells capable of producing metal compounds in an efficient manner both from a technical and an economic point of view.

Broadly considered, the electrolytic apparatus of the present invention is exemplified by a cell constituting an anode chamber having at least one metal anode but preferably a plurality of anodes mounted therein between hollow, relatively flat cathode chambers, the walls of which facing the anode or anodes constitute the cathodes, the anodes and cathodes being separated by permeable diaphragms. The flat anode or anodes are mounted in upright or vertical position between the cathode chambers.

The walls of the cathodes facing the anodes preferably are composed of perforated sheet iron or of iron wire mesh. Because of this construction they are hereinafter referred to as being "permeable." The diaphragms may be composed of asbestos, felt or other suitable material and preferably are attached to the cathodes themselves. They may enclose the flat cathode chambers on all sides exposed to or contacting with electrolyte. The anodes are constructed of the metal to be dissolved by the electrolytic reaction to be carried out in the cell. The anode may be of cast copper, but is preferably composed of mechanically pressed waste copper-containing metal.

The cell is preferably provided with one or more carbon or magnetite electrodes mounted directly beneath the anodes. Each of the cathode chambers is provided with inlet conduits for the introduction of electrolyte thereinto from which the electrolyte flows into the anode chamber. At the bottom of the anode chamber a trough is provided beneath the anode or anodes for draining the electrolyte together with the formed precipitate. The anode chamber may be separated from the trough by a grid.

The invention is illustrated in its preferred embodiments by the accompanying drawing in which:

Figure 1 is a longitudinal elevation of a preferred embodiment with part of the casing broken away. Figure 2 is a cross-section on line 2—2 of Figure 1. Figure 3 is a cross-section through a second embodiment and Figure 4 is a top plan view of a third embodiment.

2

With particular reference to Figures 1 and 2, there is illustrated a cell having a casing 10 constituting the walls of the anode chamber constructed of any suitable chemically resistant, electrically non-conducting material. In this chamber there are mounted a plurality of hollow cathodic chambers 11 alternately arranged with a plurality of anodes 12. The walls 13 of the cathode chambers are permeable to permit passage of electrolyte therethrough. The cathodes 11 have permeable diaphragms 14 secured thereto which preferably completely enclose the cathode chambers.

Each of the cathode chambers is provided with an inlet conduit 15 for the introduction of electrolyte and an outlet conduit 16 for the partial withdrawal of electrolyte from the said chamber. Each of them is also provided with a conduit 17 for the removal of hydrogen or other gases developed or employed in the apparatus.

At the bottom of the cell there is an anodic electrolyte discharge trough 18 leading to a discharge conduit 19 which in turn is connected with a solids removal apparatus 20, illustrated only diagrammatically. From this apparatus 20 a conduit 21 is connected for recycling the utilizable part of the withdrawn electrolyte. This recycled electrolyte, assisted by any suitable means, is carried through the conduit 21 to the inlet conduits 15 connected to the tops of the cathode chambers. A valved conduit 22 is connected with the conduit 21 for the introduction of fresh electrolyte.

The cell is provided with a series of auxiliary electrodes 23 suitably constructed of graphite or magnetite mounted below the anodes 12. These electrodes are energized through the poles 24 on the side of the cell.

The cell is very satisfactorily supported in a U-shaped bracket 25 having a horizontal flange 26 which supports the weight of the cell. As illustrated, the cell is supported on one side by a rod 27 leading to and embedded in the floor, the support being through an insulator 28 on top of the rod. At the other side the cell is supported from the ceiling by a rod 29 likewise connecting to the flange 26 through an insulator 28. If desired, both sides may be supported or both sides may be suspended.

The cell is provided with an inlet conduit 31 terminating in the anodic chamber in the form of a perforated pipe, through which air, oxygen, chlorine or other gas may be introduced.

With reference to Figure 3 illustrating a second embodiment of the invention, there is shown

a cell containing only two lateral cathode chambers 11 having mounted therebetween a single anode 12. Additional anodes, however, may be contained therein. The anode 12 is flanked by the diaphragms 14, the perforated cathodic plates 13 and the exterior side walls 36. These six elements (three on a side) are held together and to an internal U-shaped support 35 by means of bolts 37. Where required, the said elements are held apart by means of a suitable packing material 38. The cathodes 13 and the exterior side walls 36 are reinforced with flat iron frame strips 39. At the top of the cell there is a cover 41 for the anode chamber, serving the purpose of collecting the excess gases introduced into the cell or generated on the electrode 23 and which have not reacted in the anode chamber. This cover also serves the purpose of permitting reactions to be carried out in the anode chamber under gas pressure. The cell of this embodiment is also provided with the correspondingly numbered other elements hereinbefore described with reference to the embodiment of Figures 1 and 2.

With reference to Figure 4 illustrating a third embodiment of the invention, there is shown a cell construction wherein the cathodic perforated plates, the diaphragms 14 and the flat iron supporting strips 39 are held in place by means of the grooves 42 in the ends of the exterior cell walls 10. This embodiment is similar to the embodiment of Figure 3 to the extent that it is composed of two cathode chambers 11 having therebetween an anode 12. It is similar to Figure 1 to the extent that the exterior wall is a unitary structure and composed of like material of construction. This third embodiment is provided with the correspondingly numbered inlets, outlets and other elements illustrated in Figures 1 and 2.

The electrolytic cells of the present invention are particularly suitable for carrying out the processes of my prior applications Serial No. 616,467, filed September 14, 1945, and Serial No. 640,138, filed January 9, 1946. It is also suitable for production of the product of my application, Serial No. 628,672 filed November 14, 1945. (These applications have been abandoned and a continuation-in-part application, Serial Number 134,126 has been filed in place thereof, on December 20, 1949.)

In accordance with a process of the first mentioned prior application an alkaline-chloride electrolyte is fed through a cell containing a copper anode. In the operation the copper chlorides and monovalent copper oxides primarily produced are transformed into copper oxychloride in accordance with the following equation:

When, instead of cuprous oxide, copper hydroxide is initially produced the secondary reaction proceeds in accordance with the following equation:

When in place of cuprous oxide either bivalent copper oxide or copper hydroxide or chlorine is produced correspondingly less oxygen is required for accomplishing the oxidation.

Compounds of metals other than copper may be produced by substantially the same reactions or by other reactions in the cells of the present invention. In such case a suitable electrolyte must be selected for the particular compound to be produced. In substantially all cases the metal of the anode is dissolved first and the final prod-

uct is precipitated by secondary reactions with or without the addition of other substances. Such other substances may be either produced in the same cell or in some outside source and introduced into the cell. As in the process hereinbefore specifically described the metal ions produced in the electrolytic anodic solution generally are transformed into monovalent or polyvalent hydroxides through the action of OH ions. These metallic hydroxides may be withdrawn from the cell and used as such or they may be treated as intermediate products and employed for the production of other substances within or outside of the cells in which they are produced.

The compounds produced in the anodic solution of the cells of the present invention are generally dispersed in very finely divided form and since they are produced in what may be considered the nascent state they enter easily into additional reactions. For this and other reasons the present invention has provided inlets beneath the anodes for the introduction of gases which when introduced will readily react with the metal compounds being formed on the anodes. Among the gases which may be introduced in the said conduit or formed on the hereinbefore mentioned electrodes are included chlorine, air, oxygen, carbon dioxide, sulfuric acid and the like. The introduction of the said gases may accomplish the conversion of the metal compounds initially formed either entirely or partly (according to the volume of the gases supplied) into chlorides, oxychlorides, basic sulphates, sulphates and carbonates.

The graphite or magnetite electrodes mounted below the anodes may be varied in size and the current supplied thereto may be lessened or increased in such manner as to provide chlorine or oxygen respectively in large or small amounts.

Through these controls, the secondary reactions with the metal compounds formed on the anodes either may be totally completed or may be partially completed to provide mixtures of compounds in the final products obtained.

In the preferred operation of the process for obtaining increased yields the electrolyte is preferably fed directly into the cathode chambers and for the most part is caused to flow through the permeable cathode walls, through the diaphragms and into the anode chamber from which it is discharged together with the precipitated compounds formed.

It should be understood that the present invention is not limited to the specific details of construction except where indicated in the claims appended hereto and that it extends to all equivalents which will occur to those skilled in the art upon consideration of the terms contained therein.

I claim:

1. An apparatus for producing copper compounds from copper by electrolysis comprising a cell constituted by an anode chamber having at least one exposed copper metal anode mounted therein, a plurality of hollow, relatively flat cathode chambers mounted on the opposite sides of the anode, the walls of the cathode chambers facing the anode constituting the cathodes, inlet means for introducing electrolyte into the cathode chambers from whence it flows to the anode chamber, outlet conduit means leading from the bottom of the anode chamber capable of discharging anodic liquid and precipitates formed permeable diaphragms separating said anode and

cathodes and a graphite electrode mounted in the anode chamber below the anodes.

2. An apparatus for producing compounds from metals by electrolysis comprising a cell constituted by an anode chamber having a plurality of exposed copper anodes mounted therein, a plurality of permeable iron-walled, hollow, relatively flat cathode chambers mounted on the opposite sides of the anodes, the walls of the cathode chambers facing the anodes constituting the cathodes, permeable diaphragms separating said anodes and cathodes, means for feeding electrolyte into each of the cathode chambers, outlet conduit means for discharging electrolyte from the anode chamber at its bottom, auxiliary graphite electrodes mounted below the copper anodes and an outlet pipe for the discharge of gas from each of the cathode chambers.
